TABLE

Denis Jester, Tiburon, Calif. (68 Belvedere St.
San Rafael, Calif. 94901)

Filed May 4, 1973, Ser. No. 357,334

Term of patent 14 years

Int. Cl. D6—03

U.S. Cl. D6—177

FIG. 1.

FIG. 2.

FIG. 4.

FIG. 5.

FIG. 6.

FIG. 1 is a perspective view of a table showing my new design;

FIG. 2 is an end elevational view thereof;

FIG. 3 is a top plan view thereof;

FIG. 4 is a side elevational view thereof;

FIG. 5 is a bottom plan view thereof; and

FIG. 6 is a perspective view of a table showing an elongated modified form of my new design.

I claim:

The ornamental design for a table, substantially as shown and described.
